UNITED STATES PATENT OFFICE

CEPHAS B. ROGERS, OF DANBURY, CONNECTICUT

DESIGN FOR A CEILING FIXTURE

Application filed November 26, 1932. Serial No. 46,184. Term of patent 3½ years.

To all whom it may concern:

Be it known that I, CEPHAS B. ROGERS, a citizen of the United States, residing at Danbury, county of Fairfield, State of Connecticut, and whose post-office address is the same, have invented a new, original, and ornamental Design for a Ceiling Fixture, of which the following is a specification, reference being had to the accompanying drawing, constituting a part thereof.

In the drawing:

Fig. 1 is a side elevation of a ceiling fixture showing my new and ornamental design.

Fig. 2 is a bottom plan view thereof.

I claim:

The ornamental design for a ceiling fixture substantially as shown.

In testimony whereof I have hereunto subscribed my name this 25th day of November, 1932.

CEPHAS B. ROGERS.
